Attorney, Agent, or Firm—Wood, Herron & Evans[57] **CLAIM**

The ornamental design for a lingual orthodontic pendulum appliance, as shown and described.

DESCRIPTION

FIG. 1 is a perspective view of one embodiment of the lingual orthodontic pendulum appliance design of this invention, depicting the front, right side, and top thereof;

FIG. 2 is a front elevational view thereof;

FIG. 3 is a right side elevational view thereof;

FIG. 4 is a left side elevational view thereof;

FIG. 5 is a top plan view thereof;

FIG. 6 is a front bottom elevational view thereof;

FIG. 7 is a rear elevational view thereof;

FIG. 8 is a perspective view of another embodiment of lingual orthodontic pendulum appliance design of this invention, depicting the front, right side and top thereof;

FIG. 9 is a front elevational view thereof;

FIG. 10 is a right side elevational view thereof;

FIG. 11 is a left side elevational view thereof;

FIG. 12 is a top plan view thereof;

FIG. 13 is a front bottom elevational view thereof; and,

FIG. 14 is a rear elevational view thereof.
